UNITED STATES PATENT OFFICE.

CHARLES GEORGE JOHANNESMEYER, OF GLENDALE, OHIO.

PLANER-FEED.

1,284,353.

Specification of Letters Patent. Patented Nov. 12, 1918.

Application filed April 15, 1918. Serial No. 228,597.

To all whom it may concern:

Be it known that I, CHARLES GEORGE JOHANNESMEYER, a citizen of the United States, residing in Glendale, Hamilton County, Ohio, have invented certain new and useful Improvements in Planer-Feeds, of which the following is a specification.

This invention pertaining to planer-feeds relates to improvements in the means for transmitting motion from one of the shafts of the table-actuating system to the tool-feeding screws or rods, and the improvements will be readily understood from the following description, taken in connection with the accompanying drawings, in which:—

Figure 1 is a front elevation of a portion of a planer equipped with my improved system of feed:—

Fig. 2 a side elevation of the same:—

Fig. 3 a diagram of an exemplifying table-actuating system of gearing:—

Fig. 4 an elevation of the outer face of the main gear-guard:—

Fig. 5 an elevation of the inner face of the main gear-guard:—

Fig. 6 a rear elevation at one end of the rail, the main gear-guard and its contained mechanism appearing in vertical section in the plane of line *a* of Figs. 2, 4, 5 and 7:—

Fig. 7 an end view of the rail and the feed-mechanism carried by it, the main gear-guard being omitted: and

Fig. 8 a front elevation at the base of one of the housings, showing the reversing-gear-box with its cover removed, one of the reversing gears being shown in vertical section in the plane of line *a*, previously referred to.

A diversity of scales is employed in the drawings:—

In the drawings:—

1, indicates the planer-bed:—

2, one of the housings:—

3, the planer table:—

4, the driving-pulleys:—

5, the gears and shafts, considered as a whole, constituting the transmission sys-

tem between the driving-pulleys and the table:—

6, a selected one of the shafts of the transmission system:—

7, a gear fast on this shaft at one side of the planer:—

8, the rail:—

9, the rail-screws and rod, considered as a group:—

10, the usual ratchet gears or so-called "click-boxes" on the outer face of the rail-screws and rail-rod:—

11, a gear mounted at the end of the rail and adapted to impart intermittent rotary motion to the click-boxes:—

12, a vertically splined shaft for transmitting motion to gear 11 from the transmission system of the planer:—

13, the base-portion of a side-head: and

14, the shaft for operating by hand the elevating screw of the side-head:—

All of the above-mentioned parts, except as hereinafter stated, may be as usual and are subject to any of the usual modifications of such parts.

Proceeding with the drawings:—

15, indicates a shaft disposed under and intersecting the axis of splined shaft 12:—

16, a pinion on this shaft and engaged by gear 7, the presence of this gearing being incident to the fact that shaft 6 of the transmission system was selected on account of its location relative to the front of the housing and that its rate of turning was lower than was desired for the splined shaft: and

17, reversing gearing connecting shaft 15 with the splined shaft:—

As usual in planer-feeds, the click-boxes oscillate to predetermined degree immediately following each reversal of the planer motion, the turning of the click-boxes in one direction being effective upon the feed-screw, and being ineffective when turning in the other direction, the click-box being adjusted, as usual, to select which of its two directions of motion shall be the effective one. The splined shaft, which is to transmit the motion which is to ultimately go to

the click-box, reverses its direction of continuous turning at each reversal of motion of the planer-table, and, by means of the reversing gear 17, the direction of motion of the click-box relative to the direction of motion of the planer-feed may be selectively reversed so that the effective motion of the click-box may be caused to begin either at the beginning of the cutting stroke or at the beginning of the backing stroke of the table, and this selection may, by means of the reversing gear, be effected even while the planer is in operation.

Proceeding with the drawings:—

15 18, indicates a shaft journaled in the end of the rail parallel with the feed-screw and projecting from the end of the rail:

19, bevel-gearing connecting shaft 18 with the splined shaft:

20 20, a friction-disk fast on shaft 18 and forming the driving-member of an automatic clutch, this disk lying alongside the face of disk 11 previously referred to:

21, a spring strap clasping the friction-disk and anchored to gear 11; this strap forming the driven-member of the automatic clutch:

22, a cam-lever carried by gear 11 and cooperating with the strap to serve in releasing its grip when the cam-lever is rocked in either direction:

23, a fixed stop in the path of the cam-lever and adapted to release the strap and arrest gear 11 when the lever strikes the stop as the gear turns in one direction:

24, an adjustable fixed stop in the path of the cam-lever to release the strap and stop the gear as the gear turns in the opposite direction:

40 24^a, an arm pivoted on shaft 18 and carrying the adjustable stop 24 at its end:

25, a fixed emergency stop in the path of the cam-lever beyond the range of adjustment of the adjustable stop away from fixed

45 stop 23:

26, a worm-gear on the hub of arm 24^a:

27, a handled worm engaging this worm-gear and serving in the angular adjustment of stop 24:

50 28, a graduated dial on the hub of arm 24^a:

29, a casing or main gear-guard removably secured to the end of the rail and serving to inclose the clutch and worm-gear and to furnish an outboard bearing for the hub 55 of arm 24^a which is loose on shaft 18, this casing also carrying the index coöperating with the graduations on the dial:

30, the clutch-mechanism, etc., at the end of the rail, considered as a whole: and

60 31, similar mechanism applied to the side head.

The friction-disk oscillates in unison with the oscillations of splined shaft 12, and, while the strap is gripping the friction-disk

gear 11 moves with the friction-disk, but the 65 driving grip of the strap releases and gear 11 comes to rest when the cam-lever strikes either of the two stops 23 and 24. The oscillations of gear 11 bring about the oscillations of the click-gears, and it follows that, at each 70 reversal of the table motion, the click-gears will be turned in a given direction to the extent represented by the distance between the two stops. This distance can manifestly be adjusted by turning the worm 27 and this 75 adjustment can be made at any time regardless of whether the planer be in motion or not. The dial indicates the angular position to which stop 24 has been adjusted and it may read in arbitrary numbers or in units of 80 feeding distance.

Fixed stop 25 will obviously never be engaged by the cam-lever in the normal working of the mechanism, but if, for any reason, casing 29 and arm 24^a be removed, and the 85 planer be in motion, stop 25 acts as an emergency stop and puts a limit on the turning of gear 11 in one direction, while stop 23 serves as usual in stopping the motion in the other direction.

The illustrations set forth but one side of the planer, but it is to be understood that in cases of very wide planers the feeding mechanism may be duplicated on the other side of the planer, and it will also be understood 95 that the illustration of two feed-screws in the rail is incident to the assumed presence of two saddles on the rail.

I claim:—

1. A planer-feed comprising, a planer 100 table, a shaft reversing its direction of rotation when the motion of the planer-table reverses, a feed screw, a gear to give intermittent rotation to the feed-screw, transmitting mechanism for transmitting motion from 105 said shaft to said gear, feed-adjusting mechanism to limit the turning of said gear, and a reversing device interposed in said transmitting mechanism to change the direction of motion of said gear relative to that of 110 said shaft.

2. A planer-feed comprising, a planer table, a shaft arranged to reverse its direction of turning when the planer-table reverses, a feed screw, a gear loose relative to 115 said shaft and adapted to impart intermittent motion to the feed-screw, an automatic clutch connecting the gear and the shaft, a clutch-releasing member forming part of said clutch and traveling with said gear, a fixed stop in the path of said clutch-releasing member, an arm loose on said shaft, a stop carried by the end of said arm in the path of said clutch-releasing member, a worm-gear on the hub of the arm, and a 120 hand-operative worm engaging said worm-gear, combined substantially as set forth.

3. A planer-feed comprising, a planer

table, a shaft arranged to reverse its direction of turning when the planer-table reverses, a feed screw, a gear loose relative to said shaft and adapted to impart intermittent motion to the feed-screw, an automatic clutch connecting the gear and the shaft, a clutch-releasing member forming part of said clutch and traveling with said gear, a fixed stop in the path of said clutch-releasing member, an arm loose on said shaft, a stop carried by the end of said arm in the

path of said clutch-releasing member, a worm-gear on the hub of the arm, a hand-operative worm engaging said worm-gear, and a graduated dial carried by said arm 15 and coöoperating with a fixed index, combined substantially as set forth.

CHARLES GEORGE JOHANNESMEYER.
